UNITED STATES PATENT OFFICE

PAUL PIGNOT, OF HASTINGS, ASSIGNOR TO THE ALEX. SMITH & SONS
CARPET COMPANY, OF YONKERS, NEW YORK.

DESIGN FOR A CARPET.

SPECIFICATION forming part of Design No. 20,265, dated November 4, 1890.

Application filed October 10, 1890. Serial No. 367,640. Term of patent 3½ years.

To all whom it may concern:

Be it known that I, PAUL PIGNOT, a citizen of the United States, residing at Hastings, Westchester county, New York, have invented 5 a new and original Design for Carpets, of which the following is a specification, reference being had to the accompanying photograph, which forms a part of the same.

The invention relates to a design to be 10 worked into or upon surfaces, such as carpets or similar fabrics; and it consists in the novel configuration and grouping of figures herein specifically shown and claimed.

The accompanying photograph is a face 15 view of a carpet showing my new design.

My design consists of the body A and the border B. The body A is composed of flower forms lying on groups of shaded leaf forms.

At irregular intervals are groups of small 20 somewhat rose-shaped forms and leaf forms.

The border B is composed of an inner ornamental margin, a middle portion of flower forms resting on groups of shaded leaf forms, and groups of small and somewhat rose-shaped forms at irregular intervals, and an 25 outer margin of ornamental design containing gem-shaped forms.

What I claim as new, and desire to secure by Letters Patent, is--

1. The design for a carpet, consisting of the 30 body A, substantially as shown.
2. The design for a carpet, consisting of the border B, substantially as shown.
3. The design for a carpet, consisting of the body A and the border B, substantially as 35 shown.

PAUL PIGNOT.
